SLICING MACHINE

William J. Campbell, Indianapolis, Ind., assignor
to American Slicing Machine Company, Chi-
cago, Ill., a corporation of New York

Application January 15, 1934, Serial No. 706,717

14 Claims. (Cl. 146—102)

My invention relates to an improvement in slicing machines and has for one purpose the provision of means for protecting or guarding the cutting edge of the knife when the device is not 5 in use. Another purpose is the provision of means for permitting the gauge plate to be moved into complete guarding position. Another object is the provision of means for moving the carriage which supports the work, in order to permit the 10 gauge plate to reach a fully adequate knife edge guarding position. Other objects will appear from time to time in the course of the specification and claims.

I illustrate my invention more or less diagrammatically in the accompanying drawings, where-
in—

Figure 1 is a side elevation with parts broken away;

Figure 2 is a plan view with parts broken 20 away;

Figure 3 is an end view with parts broken away;

Figure 4 is a partial plan view similar to Figure 2 with the parts in different position;

Figure 5 is a plan view of a variant form of 25 invention;

Figure 6 is a partial end view of the structure shown in Figure 5; and

Figure 7 is a section on the line 7—7 of 30 Figure 6.

Like parts are indicated by like symbols throughout the specification and drawings.

Referring first to Figures 1 to 4, A indicates any suitable base upon which is mounted a motor 35 A¹ which, through its motor shaft A², pulley A³ and belt A⁴, drives a knife B.

The knife B is mounted on any suitable knife shaft B¹ which carries, a pulley B² about which passes the belt A⁴. B³ indicates any suitable 40 bearing sleeve for the shaft B¹. The forward face of the knife is covered, for example, by the guard plate B⁴ the details of which do not form a part of the present invention.

C is a slice receiving member to the rear of 45 the cutting plane. The gauge of the slices delivered thereto is controlled by the gauge plate C¹ which is supported, for example, upon the guiding members C² C³ which are herein shown as pins slidably penetrating corresponding sleeves C⁴ C⁵ in the base.

In order to move the gauge plate toward and 50 away from the cutting plane I provide a manual control lever D which is pivoted as at D¹ and is provided with an offset portion D² connected by a link D³ to a block or projection D⁴ secured to

the guide pin C³. It will be understood that in response to movement of the lever D about the center D¹ the guide pin C³ is given axial movement and moves the gauge plate to any desired adjustment.

EE¹ indicate tracks mounted at their ends on cross members E² which cross members are slide- 5 able on transverse tracks E³, the ends of which are secured in supports E⁴ upwardly extending from any suitable plate E⁵, the plates E⁵ being secured 10 to the base A as by the screws E⁶, the heads of which are enclosed within the base. E⁷ is a trans- 15 verse member connecting the portions E² whereby the tracks EE¹ may be moved as a unit along the transverse tracks E³.

In order to impart transverse movement to the tracks EE¹, I provide an actuating connection or rod G which is secured as at G¹ to the lower side of the member E⁷, for example to the downward extension G². It may pass through a guiding 20 bearing G³ in the base A and is provided with a terminal portion having space rollers G⁴ G⁵ which engage the opposite sides of a cam loop G⁶ which is secured to or forms part of the lever D. It will be understood from comparing the position of 25 the parts as shown in Figures 2 and 4, that move-
ment of the lever D controls both the position of the gauge plate C¹ and of the tracks EE¹. It, therefore, controls the position of the carriage H which is shown as slideable upon the tracks EE¹ 30 and as provided with the work supporting mem-
ber H¹, the forward edge of which H² normally approaches closely to the cutting plane in the posi-
tion in which it is shown in Figure 4. In Figure 4, 35 the lever D is shown in the position in which the gauge plate is most remote from the cutting plane.

As the lever D is given a clockwise movement, referring to the position of the parts in which they are shown in Figure 4, the guide C³ and thus the gauge plate C¹ are moved toward the cutting 40 plane. The cam loop G⁶ is so formed that during the normal adjusting excursion of the lever D, no axial movement is imparted to the member G. However, there is an actual cam portion G¹⁰ to the 45 loop which becomes effective when the gauge plate approaches the cutting plane. When it be-
comes effective, as in the position in which the parts are shown in Figure 2, further clockwise movement of the lever D, not merely advances the gauge plate C¹ to knife masking position, but also 50 gives an axial movement to the pin G which causes the entire track structure, including the tracks EE¹ and the carriage H to move slightly away from the cutting plane. This permits the gauge plate fully to mask the cutting edge of the knife, 55

thus insuring safety from accidental cutting when the device is in neutral position. On the other hand, when the operator wishes to employ the slicing machine, a counter-clockwise movement 5 of the lever D initially withdraws the gauge plate from its masking alignment and at the same time moves the forward edge H² of the carriage almost to the cutting plane. One important advantage of having the edge of the carriage so close to the cutting plane is that the work to be sliced is fully supported. In practise this prevents a warping 10 or drawing down of the work by leaving the forward edge unsupported by the carriage H or its work supporting member H¹. Where meat, for example fat meat like ham or bacon, is left unsupported it drags across both the gauge plate and the knife and this causes larding or the frictional disposition of grease upon the gauge plate and knife. The friction between the knife and the 15 work is increased which increases the heat caused by friction and this very much increases the tendency to deposit lard or grease. Also, the unsupported edge of the work tends to feather or draw out giving the slices a ragged edge. These 20 disadvantages are largely obviated by having the forward edge H² of the carriage closely adjacent the cutting plane. This would prevent a complete masking of the cutting edge by the gauge plate were a rearward movement of the carriage 25 or of its supports not permitted.

As a variant solution of the same problem, I illustrate in Figures 5 to 7 a structure in which the tracks JJ¹ are mounted at one end upon a transverse support J² which is pivoted as at J³ to the base A. At the opposite end they are secured to a transverse member J⁴ which is slidably mounted upon a track or pin J⁵, which, in turn, is mounted at each end upon a support J⁶ J⁷, these supports being joined at their bottom as at J⁸ 30 and secured to the base A as by the screws J⁹. The spring J¹⁰ normally urges the member J⁴ along the track J⁵ toward the cutting plane. Its movement toward the cutting plane may be adjustably controlled or limited as by the adjustment screw J¹¹, the end of which engages the limiting abutment J¹². In this form of the device there need be no direct connection between the lever D and the track structure. I simply provide a thrusting abutment in the form of the screw K opposed to an abutment K¹ on the gauge plate structure herein indicated as including the support K². The screw K may be adjustable as in the ear K³ which depends from the member J⁴. It will be understood that the spring J¹⁰ normally thrusts the member J⁴ as far as it will go 45 toward the cutting plane. The parts are so adjusted that the edge H² of the carriage or work support is normally closely adjacent the cutting plane. When the gauge plate C¹ is moved into 50 neutral or guard position, as shown in Figure 5, the engagement between the members K and K¹ forces the structure back against the spring J¹⁰. It will be realized that whereas I have described and shown a practical and operative device, nevertheless many changes might be made in the size, shape, number and disposition of parts without departing from the spirit of my invention. For example, whereas in Figures 5 and 6 I have 55 shown the track structure as pivoted at one end, it will be understood that in some circumstances both ends might be guided on tracks such as J⁵. It will also be understood that whereas I have shown in Figure 2 and following a positive means for imparting lateral movement to the tracks EE¹ 60 and the carriage H, I might dispense with the pos-

itive connection G and substitute springs such as are shown at J¹⁰ in Figures 5 and 6. The main object is to obtain a close approach of the forward edge of the carriage to the cutting plane while permitting a recession of the carriage from the cutting plane when the gauge plate is serving a guarding instead of a gauging function. I, therefore, wish my description and drawings to be taken as in a broad sense illustrative and diagrammatic rather than as limiting me to my 10 specific showing.

It will be understood that where in the claims I specify that the carriage is movable in response to movement of the gauge plate I wish this term to be interpreted broadly enough to cover the 15 movement of the carriage in response to movement of the gauge plate support or to movement in unison with the gauge plate, where some common connection is employed for imparting unitary movement to gauge plate and carriage. Examples of such means for impacting unitary movement are, of course, present in all forms of the invention herein shown and the gauge plate itself is not indicated as contacting the carriage. In one of the forms shown the gauge plate support thrusts against the support for the carriage guides, as shown in Figure 6. In another, as shown for example in Figures 2 and 4, a camming connection is employed between the carriage supporting guides and the manual lever 20 for actuating the gauge plate.

I claim:

1. In a slicing machine, a base, a knife mounted on the base and means for actuating it, a gauge plate and means for actuating it, a carriage and guiding means for guiding said carriage across the face of the gauge plate and past the cutting edge of the knife, and means for varying the distance between the carriage and the cutting plane of the knife in response to movement of the gauge plate.

2. In a slicing machine, a base, a knife mounted on the base and means for actuating it, a gauge plate and means for actuating it, a carriage and guiding means for guiding said carriage across the face of the gauge plate and past the cutting edge of the knife, and means for moving said carriage away from the cutting plane of the knife in response to movement of the gauge plate.

3. In a slicing machine, a base, a knife mounted on the base and means for actuating it, a gauge plate and means for actuating it, a carriage and guiding means for guiding said carriage across the face of the gauge plate and past the cutting edge of the knife, and means, responsive to changes in position of the gauge plate, for varying the distance between the carriage and the cutting plane of the knife when the gauge plate crosses the cutting plane.

4. In a slicing machine, a base, a knife mounted on the base and means for actuating it, a gauge plate and means for actuating it, a carriage, and a guiding track for guiding it across the face of the gauge plate and past the cutting edge of the knife, and means responsive to changes in position of the gauge plate, for bodily moving said carriage and track toward and away from the cutting plane, in unison with movement of the gauge plate when the gauge plate reaches a predetermined position adjacent the cutting plane.

5. In a slicing machine, a base, a knife mounted on the base and means for actuating it, a gauge plate and means for actuating it, a carriage, and a guiding track for guiding it across the face of the gauge plate and past the cutting edge of

the knife, and means for bodily moving said carriage and track toward and away from the cutting plane, including a connection between said track and the gauge plate actuating means.

5 6. In a slicing machine, a base, a knife mounted on the base and means for actuating it, a gauge plate and means for actuating it, a carriage, and a guiding track for guiding it across the face of the gauge plate and past the cutting 10 edge of the knife, and means for bodily moving said carriage and track toward and away from the cutting plane, including a cam connection between said track and the gauge plate actuating means.

15 7. In a slicing machine, a base, a knife mounted on the base and means for actuating it, a gauge plate and means for actuating it, a carriage, and a guiding track for guiding it across the face of the gauge plate and past the cutting 20 edge of the knife, and means for bodily moving said carriage and track toward and away from the cutting plane, the track being pivoted to the base at one end, the opposite end being movable toward and away from the cutting plane, and 25 yielding means effective normally to urge said free end toward the cutting plane.

8. In a slicing machine, a base, a knife mounted on the base and means for actuating it, a gauge plate and means for actuating it, a carriage, and a guiding track for guiding it across the face of the gauge plate and past the cutting 30 edge of the knife, and means for bodily moving said carriage and track toward and away from the cutting plane, the track being pivoted to the base at one end, the opposite end being movable toward and away from the cutting plane, and yielding means effective normally to urge said free 35 end toward the cutting plane, and adjustable means for limiting its closest approach thereto.

40 9. In a slicing machine, a base, a knife mounted on the base and means for actuating it, a gauge plate and an actuating lever therefor pivotably mounted upon the base, and an actuating connection between said lever and the gauge plate, a carriage and a guiding track for guiding 45 it across the face of the gauge plate and past the cutting edge of the knife, and means for bodily moving said carriage toward and away from the cutting plane, including a connection between 50 said carriage and said gauge plate actuating lever.

55 10. In a slicing machine, a base, a knife mounted on the base and means for actuating it, a gauge plate and an actuating lever therefor pivotably mounted upon the base, and an actuating connection between said lever and the gauge plate, a carriage and a guiding track for guiding 60 it across the face of the gauge plate and past the cutting edge of the knife, and means for bodily moving said carriage and a track toward and away from the cutting plane, including a connection between said track and said gauge plate actuating lever.

60 11. In a slicing machine, a base, a knife mount-

ed on the base and means for actuating it, a gauge plate and an actuating lever therefor pivotably mounted upon the base, and an actuating connection between said lever and the gauge plate, a carriage and a guiding track for guiding it across the face of the gauge plate and past the cutting edge of the knife, and means for bodily moving said carriage and a track toward and away from the cutting plane, including a connection between said track and said gauge plate actuating lever, and transverse guiding means for guiding said track toward and away from the cutting plane.

5 12. In a slicing machine, a base, a knife mounted on the base and means for actuating it, a gauge plate, said gauge plate being generally parallel with the cutting plane defined by the edge of the knife, and normally positioned at one side thereof, means for moving the gauge plate through a predetermined range of position, 15 into and out of the cutting plane, a carriage and means for guiding the carriage across the face of the gauge plate and past the cutting edge of the knife, the carriage being positioned on the side of the cutting plane opposite to the gauge plate 20 and being provided with an edge terminating closely adjacent the cutting plane, and means responsive to the movement of the gauge plate, for moving the carriage away from the cutting plane when the gauge plate is moved into the 25 cutting plane.

13. In a slicing machine, a base, a knife mounted on the base and means for actuating it, a gauge plate mounted on the base and means for actuating it, a carriage and guiding means for 30 guiding said carriage across the face of the gauge plate and past the cutting edge of the knife, means in connection with the carriage and guiding means adapted to permit the movement of the carriage toward and away from the cutting 35 plane, and means for moving the carriage away from the cutting plane, and in unison with the movement of the gauge plate, when the gauge plate reaches to within a predetermined distance 40 of the cutting plane, including a connection between the gauge plate actuating means and the carriage.

45 14. In a slicing machine, a base, a knife mounted on the base and means for actuating it, a gauge plate mounted on the base, a carriage and means for guiding said carriage across the face of the gauge plate and past the cutting edge of the knife, means in connection with the carriage and guiding means, adapted to permit the movement of the carriage toward and away from the 50 cutting plane, and unitary means effective normally to control the position of the gauge plate, and effective, when the gauge plate reaches to within a predetermined distance of the cutting 55 plane, to move the gauge plate and the carriage 60 in unison in the same direction.

WILLIAM J. CAMPBELL.
